UNITED STATES PATENT OFFICE.

JULIUS S. MEYER, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 13,382, dated October 31, 1882.

Application filed August 11, 1882. Term of patent 3½ years.

To all whom it may concern:

Be it known that I, JULIUS S. MEYER, of New York, in the State of New York, have invented a new and original Design for Carpets, 5 of which the following is a specification.

This invention relates to a new and original design for carpets and similar fabrics; and it consists in the novel grouping and configuration of figures hereinlater more fully described.

10 The accompanying photograph illustrates a face view of a carpet having my new design.

The ground *a* consists of a blank field partially filled with various disconnected circular and right-lined geometrical forms, all minutely 15 and symmetrically figured. Overlying this ground are various loosely-clustered flower and leaf groups.

15 *A* is a group consisting of a rose and two star-shaped flowers on a leaf-mass, with a group 20 of small flowers below, and one to the right and one above, and a blossom-spray above and to the left.

25 *B* is a smaller cluster of leaves, star-shaped flowers, and buds, and is to the right of and below the group *A*.

30 *C* consists of a central mass of long leaves with a cluster of star-shaped flowers above it, and with bunches and sprays of smaller star-shaped flowers and blossoms projecting on all sides.

D is a scattered cluster of larger and smaller star-shaped flowers and leaves in various groups, as shown.

E is a smaller group, and consists of two large star-shaped flowers on a mass of leaves 35 with a blossom spray on the left.

I claim—

1. The design for carpets, consisting of the ground *a*, substantially as shown.

2. The design for carpets, consisting of the 40 group *A*, substantially as shown.

3. The design for carpets, consisting of the group *B*, substantially as shown.

4. The design for carpets, consisting of the group *C*, substantially as shown. 45

5. The design for carpets, consisting of the group *D*, substantially as shown.

6. The design for carpets, consisting of the group *E*, substantially as shown.

7. The design for carpets, consisting of the 50 groups *A*, *B*, *C*, *D*, and *E*, substantially as shown.

8. The design for carpets, consisting of the groups *A*, *B*, *C*, *D*, and *E*, and the ground *a*, substantially as shown and described.

JULIUS S. MEYER.
